UNITED STATES PATENT OFFICE.

GLENN H. CURTISS, OF BUFFALO, NEW YORK, ASSIGNOR TO CURTISS AEROPLANE AND MOTOR CORPORATION, A CORPORATION OF NEW YORK.

TWIN-FUSELAGE CONSTRUCTION.

1,294,412.

Specification of Letters Patent. Patented Feb. 18, 1919.

Application filed October 18, 1915. Serial No. 56,602.

To all whom it may concern:

Be it known that I, GLENN H. CURTISS, a citizen of the United States, residing at Buffalo, in the county of Erie and State of New York, have invented certain new and useful Improvements in Twin-Fuselage Construction, of which the following is a specification.

This invention relates to flying machines of the heavier-than-air type, and more particularly relates to a double fuselage construction especially adapted for military aeroplanes.

With the ordinary provision of but a single fuselage in which are arranged both the seats of the pilot and observer, together with the driving mechanism and the guiding controls of the machine, a single fortunate shot by the enemy is sufficient to destroy the machine by disabling the pilot.

With the provision of an aeroplane having a double fuselage, on the other hand, seats for a pair of pilots, and also for a pair of observers, may be readily arranged to separate each pilot and observer from the occupants of the other fuselage, thus lessening the danger of destruction by half. Obstacles, however, as to the operation of the propelling mechanism of the machine and as to the flight control means must be overcome by arrangements which will obviate the possibility of destruction of the machine upon either of the pilots becoming disabled.

To this end, the present invention involves an aeroplane construction based upon the use of spaced fuselages which has for its principal object the provision of separate propelling mechanisms for each fuselage; the arrangement of seats for a pilot and an observer within each fuselage, from either of which seats the propelling mechanism attached to both fuselages may be controlled; and the provision of common means extending between the pilots' seats of the separated fuselages for the control of at least one of the rear guiding surfaces with which the machine is equipped in a novel manner.

The above, and additional objects of a

similar nature which will be hereinafter more specifically treated, are accomplished by such means as are illustrated in the accompanying drawing, described in the following specification, and then more particularly pointed out in the claims which are appended hereto and form a part of this application.

With reference to the drawings wherein there is illustrated one of the preferred embodiments of the invention:

Figure 1 is a view in perspective of a twin fuselage aeroplane as viewed from the rear during flight;

Fig. 2 is a side elevation of a portion of the craft illustrating diagrammatically the motor throttle control system, and

Fig. 3 is a similar view illustrating in top plan said system.

In its general aspects the aeroplane shown as equipped with the twin fuselage of this invention is of the tractor biplane type, although it will be obvious that no restrictions should be inferred to disown the employment of the double fuselage hereby disclosed with aeroplanes having any type of supporting surface or any type of propelling mechanism.

The twin fuselages are designated by the respective numerals 1 and 2, and are similarly formed in every characteristic. Each is of the streamline formation approved by customary practice; each fuselage is equipped with its own engine and a tractor blade directly driven thereby; each fuselage has engine section wing posts 3 upon which are supported the upper wing panel 4 of the engine section, which may be suitably stayed between both fuselages as is denoted by the numeral 5. The lower engine wing panel 6 is connected directly to each fuselage and extends therebetween. This construction permits the remainder of the main supporting surfaces, including the upper lateral wings 7 and the lower wings 8 to be respectively hinged, as is denoted at 9, to the upper wing panel and directly to separate fuselages.

Wing posts 10 vertically connect the spaced supporting surfaces of the biplane type, such posts being cross-braced by wires 11 in a well known manner which requires no specific exposition.

In Figs. 2 and 3 I have illustrated diagrammatically the control means for simultaneously controlling the separate motors. This means consists of a shaft 10' ar-
10 ranged to extend into the pilot's cockpit of each fuselage. Said shaft is terminally equipped with pulleys 11' over which throttle control leads 12' are trained. The control leads extend forwardly from the shaft
15 10' to pulleys 13' mounted respectively upon the shafts 14' of the carbureters for the separate motors. Through this arrangement the separate motors may be simultaneously throttled or controlled.

20 An observer's pit 12 is arranged forwardly in each fuselage, being surrounded by the usual pit cowl 13 to protect the occupant. Immediately behind the observer's station in each fuselage is arranged accom-
25 modation for a pilot, this pit 14 containing the guiding controls of the machine, as well as of both engines, although these latter controls may, as has been proposed, be shared with the observer's pit.

30 Commonly supported upon the tail of each of the fuselages 1 and 2 is the laterally overhanging, substantially horizontal stabilizing plane 15, to the rear edge of which is hinged a plurality of elevating surfaces 16, such surfaces being arranged between the fuselages and laterally therebeyond and having their lateral edges so disposed, or cut away as shown at 17, as to permit lateral movement of rudders 18 which are vertically
35 pivoted to the tail post of each separate fuselage. Vertical stabilizing fins 19 are also separately carried by the fuselages to overlie the common horizontal stabilizer.

Control of the guiding or directional con-
45 trol surfaces 16 of the craft is effected by the provision of a rockshaft 20 which connects the fuselages and extends into each pilot's pit 14, being arranged for oscillation longitudinally of the machine. At its
50 extremities, control columns 21 are erected to carry the rotatable control wheels 22, which are also oscillatable with the shaft 20. These wheels control steering cables 23 which extend rearwardly from each fus-
55 lage to the laterally projecting rudder braces 24 whereby movement of the rudder surfaces may be independently accomplished. Oscilla-
60 tion of the rockshaft 20, however, simultaneously moves the elevators 16 through the medium of shaft arm 25 and cables 26 which connect such arms with the elevator braces 27. Although each rudder is disclosed as separately operated and of sufficient area to

provide for perfect control by its independent operation, it is to be understood that 65 appropriate means may be provided whereby simultaneous movement of the rudders, like the elevators, can be effected.

While the machine here shown is of the land alighting type, and as such is equipped 70 with running gear 28 common to both fuselages, it will be apparent that an adaptation of this invention in aeroplane fuselages could readily be made for use in connection with hydroaeroplanes or other aerial craft, 75 by consultation with the above disclosures. The form of landing gear illustrated comprises a single set of running wheels which are spaced widely apart on a common axle and braced to the wing beams 29, shown in 80 dotted lines. Insurance of great stability is thus given the machine in operating on the ground.

An aeroplane constructed in accordance with the foregoing is well fitted for military uses, particularly those of the reconnaissance. The provision of the spaced fuselages with the consequent distribution of the increased crew renders the machine much less liable to destruction. Where but 90 a single observer and aviator form a machine's crew, placing the pilot out of action renders the machine useless and its mission a failure. Merely doubling the crew of an ordinary flying machine would have no 95 greatly beneficial effect, unless some particular disposition were made of the added numbers which should prevent the destruction of those controlling the machine by one well-placed shot. In the present instance both 100 of the aviators must be disabled in order to interfere with the normal control of the machine. Even the placing of the entire crew of one fuselage out of commission fails to terminate the flight as the remaining 105 aviator for the reason that he (the remaining aviator) is able to operate both motors and one or both of the directional control surfaces without aid or adjustment.

This multiplied factor of safety and the 110 assurance that such valuable information as has been gathered in the reconnaissance has a doubled protection until received at headquarters is one incalculable advantage possessed by the flying machine provided by 115 this invention over former types in the art. An additional advantage is that more reliable and accurate data may be attained by the employment of two observers working in unison for the comparatively short duration of the flight which forces a single observer to depend upon his memory for details he has no time to record in view of the more important facts. In event of the death of the single observer, much of his 120 125 information perishes with him, a disaster

having slight chance of occurrence with use of the fuselage arrangement contemplated by this invention.

Realizing, however, that conditions current with the adoption of this invention may later be varied to a considerable extent, it is desired to emphasize the fact that corresponding alterations in the reduction of the invention to practice may be resorted to in a manner limited only by a just interpretation of the claims defining the scope of this machine.

What is claimed is:

1. In a flying machine, twin fuselages, supporting surfaces carried conjointly by the fuselages, a motor mounted in each fuselage and a propeller for each motor.
2. In a flying machine, spaced fuselages, a motor for each fuselage, supporting surfaces conjointly carried by the fuselage and a seat in each fuselage.
3. In a flying machine, spaced fuselages, supporting surfaces conjointly carried by the fuselages, control surfaces arranged on the tails of the fuselages and a pilot's seat in each fuselage.
4. In a flying machine, spaced fuselages, supporting surfaces conjointly carried by the fuselages, control surfaces arranged on the tails of the fuselages and an observer's seat in each fuselage.
5. In a flying machine, spaced fuselages, supporting surfaces conjointly carried by the fuselages, control surfaces arranged on the tails of the fuselages and seating arrangements for the crew of the machine designed to apportion a pilot and an observer to each fuselage.
6. In a flying machine, spaced fuselages, supporting surfaces conjointly carried by the fuselages, driving mechanisms mounted within the separate fuselages, and means operable from either fuselage for controlling either or both of said mechanisms.
7. In a flying machine, spaced fuselages, supporting surfaces conjointly carried by the fuselages, an engine mounted within each fuselage, and propellers, for the machine directly connected to respective engines.
8. In a flying machine, aerially supported twin fuselages, a motor for each fuselage, control surfaces for the fuselages and means to operate said surfaces and both motors from either fuselage.
9. In a flying machine, aerially supported twin fuselages, a motor for each fuselage, a pilot's seat for each fuselage, control surfaces for both fuselages separately and in common, and means to control the entire machine and its parts from either of said pilots' seats.
10. In a flying machine, a plurality of

fuselages, supporting surfaces conjointly carried by the fuselages, a stabilizing plane supported by both fuselages, elevators pivoted to said stabilizing plane, and means in common extending between the fuselages and connected to said elevators for similar operation of the latter from any one fuselage.

11. In a flying machine, a plurality of fuselages, main supporting surfaces conjointly carried by the fuselages, a stabilizing plane supported on all of the fuselages, a rock-shaft connected to the fuselages, movable guiding means supported upon said stabilizing plane, and control means mounted in each fuselage and connected to said rock-shaft for simultaneous actuation of said guiding means.

12. In a flying machine, an engine section including spaced fuselages, upper and lower engine section panels, supporting surfaces hinged to said upper engine section panel, and additional supporting surfaces hinged directly to each fuselage.

13. In a flying machine, an engine section including separate fuselages, an engine panel wing post forming a part of each fuselage, a wing panel commonly erected upon the posts of all the fuselages, a lower wing panel connecting adjacent fuselages, and upper and lower supporting surfaces for the machine respectively hinged to said upper wing panel and said fuselages.

14. In a flying machine, a pair of separated fuselages, supporting surfaces conjointly carried by the fuselages, a separate steering surface for each fuselage, elevating surfaces in common with both fuselages, a pilot's seat in each fuselage, and control means mounted within each fuselage and connected for the similar and simultaneous actuation of one of said surfaces from the pilot's seat of each fuselage.

15. In a flying machine, a plurality of fuselages, main supporting surfaces conjointly carried by the fuselages, movable guiding surfaces for the machine, a rock-shaft common to all the fuselages, a control column mounted in each fuselage for connection to said shaft, and a wheel mounted for rotation upon each column and for oscillation with said shaft, said wheel and said shaft being connected to respective guiding surfaces whereby the latter may be identically actuated from any or all of the fuselages.

16. In a flying machine, connected fuselages, supporting surfaces, an engine in each fuselage and a seat in each fuselage.

17. In a flying machine, separate fuselages, a motor for each fuselage and means operable for either or both fuselages to control both motors.

18. In a flying machine, separate fuselages, separate control surfaces arranged respectively at opposite sides of the fore and aft axis of the craft, and means operable from either or both fuselages to control said surfaces.

19. In a flying machine, separate fuselages, a motor mounted forwardly in each

fuselage, a tractor propeller for each motor, control surfaces, means for operating the control surfaces from either fuselage, and means for controlling both motors from either fuselage. 10

In testimony whereof I affix my signature.

GLENN H. CURTISS.
